TELEPHONE BOOTH

Percival H. Sherron, Jamaica, N. Y.

Application March 10, 1954, Serial No. 29,462

Term of patent 14 years

(Cl. D13—1)

To all whom it may concern:

Be it known that I, Percival H. Sherron, a citizen of the United States, residing in Jamaica, Long Island, county of Queens, State of New York, have invented a new, original, and ornamental Design for a Telephone Booth, of which the following is a specification, reference being had to the accompanying drawing, which forms a part thereof.

The figure is a perspective view of a telephone booth embodying my new design. The side and back of the top of the telephone booth not shown are similar to the side shown.

I claim:

The ornamental design for a telephone booth, as shown and described.
